UNITED STATES PATENT OFFICE.

CHARLES J. VAN DEPOELE, OF CHICAGO, ILLINOIS.

SYSTEM OF MOTORS FOR ELECTRIC RAILWAY-BRAKES.

SPECIFICATION forming part of Letters Patent No. 352,167, dated November 9, 1886.

Application filed June 16, 1886. Serial No. 205,352. (No model.)

To all whom it may concern:

Be it known that I, CHARLES J. VAN DEPOELE, a citizen of the United States, residing at Chicago, in the county of Cook, State of Illinois, have invented certain new and useful Improvements in Systems of Motors for Electric Railway-Brakes, of which the following is a specification.

The present invention relates to improvements in systems of operating electric railway-brakes; and it consists in such an arrangement of the electric circuits throughout a train, and of electro-dynamic motors and brake mechanism upon the desired number of cars thereof, that the brakes can be applied to or removed from the wheels by the power developed in the motors when supplied with proper current, and the motors themselves can be thrown into action for either purpose by the manipulation of suitable switches, all of which can be brought to a single point, thereby placing the entire system under the control of a single operator, who may be located at either end, or, in fact, at any point on the train.

The system is illustrated in the accompanying drawings, in which Figure 1 is a view in elevation, showing a car which may form a portion of a train, said car being provided with braking mechanism according to my invention. Fig. 2 is an elevation, partly in section, of a separable slip joint or coupling by which the conductors carried by each car are connected throughout the train. Fig. 2^a is a detail showing one of the contact-springs of the coupling. Fig. 3 is a diagram illustrating one method of reversing the direction of rotation of the armature of the motors. Figs. 4 and 5 represent modifications thereof.

Similar letters denote like parts throughout. In the drawings, A is the bed or lower portion of a car, which may form a portion of a train.

B B are the wheels. b b are brake-shoes bearing against said wheels, the shoes being supported on beams C, suspended from the under side of the car or from the frame-work of the truck by links D in the well-known manner, the usual springs, d, being also provided for the purpose of throwing the brake beams and shoes away from the wheels when released. Brake-levers E are secured to the brake-

beams, and their lower ends connected by a rod, e. From the upper ends of the levers E extend draft-rods F, which extend to and are connected with an electric motor, G, in any suitable manner, but preferably as hereinbefore shown and described in my Patent No. 347,904, August 24, 1886, excepting that screw-threaded shafts extend from each end of the armature-shaft, instead of from one only, and two sets of translating devices are provided, the systems being united through the rod e, the object being to secure a powerful and steady pull on the draft-rods F when the motor rotates in one direction, and an equally steady thrust which will release the brakes when the motor is caused to rotate in the other.

The motors G throughout the train will all be connected to a circuit leading from a suitable point—as, for instance, in the manner described in Letters Patent No. 324,899, heretofore granted to me, and No. 348,360—special means being provided for reversing the direction of rotation of the armatures of the motors without changing their electrical connections or the necessity for manual interposition or interference. The circuit-connections can all be made when making up the train. Each motor is provided with suitable permanent working-conductors, which are seen in Fig. 1 in the form of cables 1 2. These are permanently secured in some safe and convenient position on the car, their terminals depending therefrom, as do the well-known air-brake hose, like which they are provided with couplings L M at their extremities, the parts M fitting over and being secured to the parts L of the next car, and so throughout the train.

The coupling itself is a simple device, the part L thereof consisting of a number of metallic rings, l, assembled together, each succeeding ring being larger than the preceding and separated therefrom by a band of insulation, l', and each ring permanently connected to one of the conductors forming the cable 1, and there being as many rings as conductors in the cables. The part M fits over the part L, and corresponds therewith in its internal configuration, each alternate step being provided with an annular spring, m, that is permanently connected with one of the conductors forming the cable 2, so that when the part

M is forced over the part L the annular springs will fit tightly over the annular terminals, making a thoroughly good electrical contact. A pin projecting from the part L fits into a slit in the part M, by which accidental separation of the two is prevented. I may, however, form the annular rings with a depression or groove in their peripheries, as shown in Fig. 2^a, and into which the ends of the springs will fit, thereby holding the parts with sufficient force to withstand ordinary jarring and swinging between the cars, yet permitting the coupling to open and separate without injury whenever the cars are uncoupled.

15 In Fig. 3 is shown two series wound motors connected in multiple arc to the positive main conductor P, leading from a suitable source of electricity, K, the return-circuit being through one or other of the conductors N N', the reversal of the motion of the armature being produced by displacing the commutator-brushes *i*, which is accomplished by means of the solenoids H H', the plungers of which are connected thereto in any suitable cylinder, and 20 by which they can be moved around the commutator in the usual manner. It will be understood that when the return-circuit is closed through one or the other of the conductors N N' by means of the switch *n*, the solenoid included in the circuit which is closed will become energized and draw in its core, and thereby move the commutator-brushes to the most favorable working position for one direction of rotation or the other.

25 In Fig. 4 is shown a pair of motors and two main circuits. The field-magnet coils of both motors are permanently connected in multiple arc between the main conductors P' N', while the armatures are similarly connected in a second main circuit, P² N². The direction of rotation of the armatures is controlled through a circuit-reversing switch, I, by which the current in the armature-circuit can be made to flow in either direction with respect 30 to that in the field-magnet.

35 In Fig. 5 a slightly modified arrangement is shown, in which the coils of the field-magnets of the motors are connected in series, as also are the armature-coils. The two circuits are, however, as in the preceding instance, separate and distinct, so that by means of a circuit-reverse switch, I, located at some convenient point, as in the previous instance, the current in the armatures can be changed with respect 40 to their field-magnets, and thereby cause them to rotate in the desired direction by merely changing the switch.

45 Having described my invention, what I claim, and desire to secure by Letters Patent, is—

1. In an electric railway-braking system, the combination of a series of electric motors, braking mechanism connected thereto adapted to be actuated by said motors to apply or release the brakes, and electric circuits and connections, whereby all the motors may be simultaneously thrown into operation in the desired direction, substantially as shown and described. 65

2. In an electric railway-braking system, the combination of a series of electric motors and mechanical connections between the motors and the brake mechanism for operating the same, a circuit extending throughout the train and including the field-magnets of the brake-actuating motors, a second circuit also extending throughout the train and including the armatures of said motors, and a current-reversing switch in said motor-circuit, whereby the direction of rotation of said armatures can be controlled from a single point. 70

3. In an electric railway-braking system, the combination, with suitable working-conductors, of the separable slip joint or coupling consisting of a part formed of a number of annular terminals assembled together and separated by suitable insulation, and a cup-shaped part adapted to receive the annular terminals and containing a corresponding number of annular springs fitting over said terminals, substantially as shown and described. 75

4. The combination of the cable 1, the part L, consisting of annular terminals corresponding in number to the conductors in the cable, said terminals being of graduated sizes and separated by suitable insulation, and the part M, consisting of a cup-like portion containing annular springs corresponding in number to the said conductors and arranged to fit over and grasp the annular terminals of the part L, substantially as set forth. 85

5. The combination, with a car, of a motor mounted thereon, shafts extending from each end of the armature-shaft and oppositely screw-threaded, brake mechanism, substantially as described, and draft-rods extending from the brake mechanism to the opposite ends of the extended armature-shaft, whereby the rotation of the armature of the motor will draw or thrust on both ends of the brake system and apply or release the brakes in both directions simultaneously, as set forth. 90

In testimony whereof I hereto affix my signature in presence of two witnesses.

CHARLES J. VAN DEPOELE.
